(57) CLAIM

The ornamental design for a picture frame, as shown and described.

DESCRIPTION

FIG. 1 is a front view of an exemplary embodiment of a picture frame according to the subject invention; and,

FIG. 2 is a rear view of the picture frame of FIG. 1. It is stated that any broken line—showing of structure is for illustrative purposes only and forms no part of the claimed design.

1 Claim, 2 Drawing Sheets

FIG. 1

FIG. 2
